PUMP

Eugene L. Kilbourn, Marengo Township, Calhoun County, Robert E. Buckner, Battle Creek, and Norman W. Klootwyk, Marshall, Mich., assignors to S. H. Leggett Company, South Marshall, Mich., a corporation of Michigan

Filed Oct. 2, 1964, Ser. No. 82,008

Term of patent 14 years

(Cl. D65—1)

FIGURE 1 is a top plan view of a pump embodying our new design;

FIGURE 2 is a front elevational view thereof;

FIGURE 3 is one side elevational view thereof;

FIGURE 4 is the opposite side elevational view thereof;

FIGURE 5 is a rear elevational view thereof; and

FIGURE 6 is a bottom view thereof.

The dominant features of our design reside in the portions shown in solid lines. The relative positions of the handle and discharge spout of the pump are varied in several of the figures to improve the disclosure thereof.

We claim:

The ornamental design for a pump, as shown and described.
